UNITED STATES PATENT OFFICE.

ALPHONSE OUELLETTE, OF FALL RIVER, MASSACHUSETTS.

INTERMITTENT FEELER MECHANISM FOR LOOMS.

Application filed July 13, 1926. Serial No. 122,104.

This invention relates to a feeler for looms, which is tripped intermittently as long as there is a considerable working supply of filling on the bobbin, but remains in feeling position when the filling on the bobbin approaches exhaustion, so as to feel the condition of the filling at each detecting beat.

The object of the present invention is to provide a feeler which has all the advantages of the intermittent operation above mentioned, and which is at the same time simple and inexpensive in construction, and easily adapted to any loom now in use.

The specific construction and operation of my improved feeler mechanism, and the advantages resulting therefrom will be more particularly explained in connection with the accompanying drawing, which illustrates the preferred embodiment thereof.

20 In the drawing:

Figure 1 is a side elevation of a portion of a loom having the invention installed thereon.

Figure 2 is a plan view thereof.

25 Figure 3 is a front elevation of the invention with some of the associated parts shown in section.

Figure 4 is a detail view of the trip mechanism.

30 The invention is illustrated in connection with a feeler 5, which is supported in the usual relation to the bobbin 6 by a slide 7, which is mounted in a casting 8 connected with the loom side 9. A coiled spring 10 is mounted on the slide 7 between the front end of the casting 8 and a shoulder 11 formed on the slide 7, and urges the latter, and the feeler 5 carried thereby, toward the bobbin. The slide 7, however, is normally held in its forward position by a latch 12, which engages a shoulder 13 formed on the slide.

35 The latch 12 is mounted on a pivot bolt 14, which is supported in a pair of ears 15 secured to the casting 8. A contractile spring 16 is attached at one end to a pin 17 secured in the latch, and is attached at its other end to a hook 18 secured to the side of the casting 8, so that the spring 16 normally acts to hold the latch 12 behind the shoulder 13.

40 The latch 12 is formed with a slotted ear 19, extending outwardly from the pivot bolt 14, and a vertical bar 20 cooperates with the slotted ear 19 to retract the latch 12, and trip the feeler under certain conditions. The

upper end of the bar 20 passes through the ear 19, and is formed with a longitudinal slot 21, in which a stud bolt 22 is adjustably secured. The lower portion of the vertical 60 bar 20 is guided in a bracket 23 secured to the loom side 9. A contractile coiled spring 24 is attached at one end in a hole 25 formed in the bar 20, and is connected at its other end to a flange 26, extending laterally from the bracket 23. The lower end of the bar 20 is adapted to ride on the rim of a wheel 27 secured to the take-up shaft 28. The stud bolt 22 is so adjusted that as long as the lower end of the bar 20 rides on the rim of 70 the wheel 27, the latch will remain in engagement with the shoulder 13 of the slide 7. The wheel 27, however, is formed with a number of notches 29 in its periphery, and when the lower end of the bar 20 drops into 75 one of these notches, the bolt 22 strikes the ear 19 and actuates the latch 12 to trip the feeler.

45 The wheel 27 is shown in the drawing as having three notches 29, so that if the wheel makes one revolution for every seventy-eight picks, the feeler will be tripped once for every twenty-six picks. As long as there is a considerable working supply of filling on the bobbin, the slide 7 will be returned at 80 the next detecting beat, and will remain latched until the lower end of the bar 20 reaches the next notch 29. If, however, the filling on the bobbin is approaching exhaustion, it will not be sufficient to return the 85 slide 7 far enough for the latch to engage the shoulder 13 again, so that the feeler will remain in feeling position, and will feel the condition of the filling at each detecting beat until the bobbin is changed, whereupon the 90 intermittent action of the filler is resumed.

50 By the use of the mechanism above described, the feeler normally acts only once for every twenty-six picks, thereby avoiding 100 the cutting of the filling, which would result if the feeler acted at every pick. By means of the construction above described, this intermittent feeler action may be attained at a very moderate expense. Its 105 action is simple and positive, and it may be easily adapted to any type of loom now in use.

55 While I have shown and described in detail the construction of one form in which the invention may be embodied, it is apparent that many of the details thereof may be modified to a considerable extent without 110

any material departure from the salient features of the invention as set forth in the claims.

What is claimed is:

- 5 1. In a feeler mechanism for looms, the combination of a feeler, a slide on which the feeler is mounted, a latch normally engaging the slide to hold the feeler in inoperative position, means for advancing the slide and feeler toward the bobbin when the latch is tripped, an ear projecting outwardly from the latch and having a slot therein, a bar 45 with one end projecting through said slot and having an abutment thereon, a bracket in which the other end of the bar is guided, a wheel adapted to be connected with the take-up mechanism with its rim engaging 50 the last-mentioned end of said bar, said rim having notches therein, and means for projecting the bar into successive notches as the wheel rotates and thereby causing said abutment to engage the ear on the latch to trip 55 the latter.
- 10 2. In a feeler mechanism for looms, the combination of a feeler, a slide on which the feeler is mounted, a latch normally engaging the slide to hold the feeler in inoperative position, means for advancing the slide and feeler toward the bobbin when the latch is tripped, an ear projecting outwardly from the latch and having a slot therein, an upright bar with its upper end projecting through said slot and having an abutment 60 thereon above the ear, and means for intermittently lowering the bar to cause the abutment to engage said ear and trip the latch, thereby permitting the feeler to be advanced toward the bobbin.
- 15 3. In a feeler mechanism for looms, the combination of a feeler, a slide on which the feeler is mounted, a latch normally engaging the slide to hold the feeler in inoperative position, means for advancing the slide and feeler toward the bobbin when the latch is tripped, a stiff upright bar guided 65 for movement up and down, an abutment secured to the bar near the upper end thereof and engageable with the latch to trip the same when the bar is moved downwardly, a wheel adapted to be connected with the take-up mechanism so that the lower end of 70 said bar rides on the rim of the wheel, thereby normally supporting the bar with the abutment above the latch, said rim having a notch therein, and means for causing the bar to drop into said notch to trip the latch.
- 20 4. In a feeler mechanism for looms, the combination of a feeler, a slide on which the feeler is mounted, a latch normally engaging 75
- 25 5. In a feeler mechanism for looms, the combination of a feeler, a slide on which the feeler is mounted, a latch normally engaging
- 30 6. In a feeler mechanism for looms, the combination of a feeler, a slide on which the feeler is mounted, a latch normally engaging
- 35 7. In a feeler mechanism for looms, the combination of a feeler, a slide on which the feeler is mounted, a latch normally engaging
- 40 8. In a feeler mechanism for looms, the combination of a feeler, a slide on which the feeler is mounted, a latch normally engaging

the slide to hold the feeler in inoperative position, means for advancing the slide and feeler toward the bobbin when the latch is tripped, an ear projecting outwardly from the latch and having a slot therein, a bar 45 with one end projecting through said slot and having an abutment thereon, a bracket in which the other end of the bar is guided, a wheel adapted to be connected with the take-up mechanism with its rim engaging 50 the last-mentioned end of said bar, said rim having notches therein, and means for projecting the bar into successive notches as the wheel rotates and thereby causing said abutment to engage the ear on the latch to trip 55 the latter.

4. In a feeler mechanism for looms, the combination of a feeler, a slide on which the feeler is mounted, a spring-held latch pivotally mounted on an axis parallel to said slide 60 and at one side thereof, a shoulder on said slide with which the latch normally engages to prevent the slide and feeler from advancing toward the bobbin, an ear projecting outwardly from said latch and having a slot 65 therein, an upright bar with its upper end projecting through said slot and having an abutment thereon, a bracket in which the lower end of the bar is guided, a wheel adapted to be connected with the take-up 70 mechanism with its rim engaging the lower end of the bar, said rim having notches therein, and means for projecting the bar into successive notches as the wheel rotates and thereby causing said abutment to engage 75 the ear on the latch to trip the latter.

In testimony, that I claim the foregoing as my own, I have hereto affixed my signature.

ALPHONSE OUELLETTE.
